UNITED STATES PATENT OFFICE.

RICHARD SYLVESTER, OF WILMINGTON, DELAWARE, ASSIGNOR TO E. I. DU PONT DE NEMOURS AND COMPANY, OF WILMINGTON, DELAWARE, A CORPORATION OF DELAWARE.

IDENTIFICATION DEVICE.

1,224,038.

Specification of Letters Patent. Patented Apr. 24, 1917.

Application filed February 16, 1917. Serial No. 148,929.

To all whom it may concern:

Be it known that I, RICHARD SYLVESTER, a citizen of the United States, residing at Wilmington, in the county of New Castle 5 and State of Delaware, have invented new and useful Improvements in Identification Devices, of which the following is a specification.

This invention relates to certain novel and 10 useful improvements in identification devices.

As is well known, it is not uncommon for a large industrial concern of the present day to have thousands of employees upon its 15 pay-roll, and even though the business of such concern be divided into various departments, each department usually has so many employees or workers connected therewith that it is practically impossible for the superintendant or other officer in charge of a 20 department to be personally acquainted with each individual under his supervision, and naturally, the officers and clerks in charge of the books and records at the office of the 25 concern are personally unacquainted with the majority of the employees in the shops or other departments of the plant. Therefore, it is the practice, especially with very 30 large manufacturing concerns, to give each individual employee an identifying number by which such employee is indicated and identified upon the pay-roll and other records of the concern.

But usually there is no means provided 35 for detecting impersonation or fraud such as might occur for instance where one individual, personally unknown to the officer in charge, might assume the identifying number of and pass himself off as another 40 who might also be personally unknown to the officer, who could not therefore detect the fraud.

In carrying out my invention, therefore, it is my purpose to provide an identification 45 device in the nature of a badge, medallion, pocket piece or the like, which is adapted to be worn or carried by the person to be identified, and which device in addition to exhibiting a particular indicating character, such as a number, by which the person is known and identified on the books or records of the concern, will also have associated 50 with the number or indicating character a

photograph of the person thus reducing to a minimum errors, mistakes and fraud which 55 might arise through confusion of personalities or other reasons.

Still a further object of my invention is the provision of an identification device which will be found particularly serviceable 60 and convenient in large industrial establishments which are divided into various departments, inasmuch as each device, in addition to identifying a particular person by number and photographic likeness, is also adapted 65 to designate the particular department with which such person is connected, so that should a person wearing one of these devices enter a department other than the one to which he is assigned, or which the device indicates, his presence and the fact that he does not belong to the department may be ascertained at a glance by the official in 70 charge who may then make an investigation to determine if such person's presence in the 75 department is authorized or unauthorized.

Furthermore, I propose to provide an identification device which will be found useful in assisting the members of the office force of the concern to check up or verify 80 the pay-roll in connection with the payment of wages to the employees. For instance, the books of the concern may contain the identifying number of an employee and his autographic signature opposite the same. 85 Should the paymaster be suspicious that a person exhibiting a particular badge or identifying device for the purpose of receiving wages is not the person to whom the badge or device belongs, he may demand such person's autographic signature and then compare it with the signature opposite the particular identifying number on the book to determine the right of the person to receive 90 the wages. 95

It is also my purpose to provide an identification device having a back plate or face which is marked or stamped with the name of the company or concern, or has thereon other matter identifying the same using the 100 device, and as the back plates or faces of all of the badges or devices are similar and bear the same data, these plates may be produced in bulk, in great quantities at a very low cost.

Furthermore, I propose to provide an

identification device which will embody the desired features of simplicity, reliability, accuracy and convenience in use.

With the above recited objects and others of a similar nature in view, my invention consists in the construction, combination and arrangement of parts set forth in and falling within the scope of the appended claims.

10 In the accompanying drawings:

Figure 1, is a face view of an identification device embodying my invention, in this instance the device being in the form of a medallion or badge.

15 Fig. 2, is a back view of the device shown in Fig. 1.

Fig. 3, is a detail view in perspective of the annular spider forming part of the device.

20 Fig. 4, is a vertical cross-sectional view taken centrally through the badge shown in Fig. 1.

Fig. 5, is a perspective view of a conventional form of pocket case with a modified 25 form of my invention associated therewith.

Fig. 6, is a cross-sectional view taken through the modified form of the device on the line 6—6 of Fig. 5, the pocket case being omitted.

30 Referring now to Figs. 1 to 4 inclusive, wherein a preferred embodiment of my invention is shown, the numeral 1 indicates the back plate which is preferably in the nature of a circular sheet metal disk of 35 suitable size and is adapted to be stamped, impressed, embossed or otherwise marked with suitable data indicating the concern using the device, this marking being indicated at 2 in Fig. 2. Adapted to bear

40 against the inner face of this back plate 1 is an annular spider 3 which in its preferred form is shown in detail in Fig. 3. This spider embodies two concentric rings, an inner ring 4 and an outer ring 5, the two 45 rings being connected by the radial arms 6. The inner ring 4 is preferably provided with a single annular flange 7 so that such ring is L-shape in cross-section, while the outer ring 5 is preferably formed with two

50 annular flanges, shown at 8, so that this outer ring is U-shape in cross-section, and the arms 6 are also preferably U-shape in cross-section. Adapted to be framed within and by the inner ring 4 is a photograph 55 9, which may be a likeness of the employee to whom the badge is assigned, and this photograph may have printed or otherwise marked thereon suitable indicia associating the original of the photograph with his or

60 her employment. Such indicia may be in the form of an identifying character preferably in the nature of a number or numbers shown at 10 so that not only will the employee be identified by his photograph, but 65 may be identified also by the number as

sociated with the photograph, such number corresponding to the employee's number on the books or records of the employer. The inner face 11 of the back plate 1 is preferably provided with color or other indicia 70 distinctively marked to indicate the particular department of the concern to which the badge and the employee wearing the same belong, and each department is intended to have the badges thereof clearly 75 distinguishable from the badges of the other departments. For instance, if a concern has four departments, known as departments "A", "B", "C" and "D", the faces 11 of the badges of department A may be colored 80 "red"; those of department B, "green"; those of department C, "white"; and those of department D, "blue". As will be understood, said color indicia does not detract attention from the photograph; on the contrary, such indicia will form a background for the photograph tending to render the latter more prominently or distinctively displayed, enabling the watchman or inspector to rapidly identify the person carrying the 85 device. This idea of distinguishing the various badges of the different departments may be carried out in various other ways other than that above recited, and instead of applying the color or other distinguishing marking directly to the face 11, colored 90 disks, mats or the like of cardboard, fabric, paper or other suitable substance may be applied or placed against the inner face 11. Or, if desired, a particular department, 95 division or section of a plant or establishment may be indicated by positioning a letter or other mark or insignia within the circle or border containing the photograph and adjacent or to one side of the letter. 100 For example, in the taking of the photograph a letter or other mark or insignia cut from metal or other suitable material which will preferably photograph white, may be positioned adjacent the person or subject 105 and the photograph then taken, so that when such photograph is printed and fastened in position within the holder or border, the letter, mark or insignia, in a clearly contrasting or otherwise distinguishing color, such for instance as white, against the brown background of the photograph, will appear in conjunction with or to one side of the actual picture or image of the subject. It will be evident that when the 110 badges are so distinguished, a person wearing a badge of one department upon entering another department would immediately 115 become known as not belonging to the department where he was present at the time. 120 After the photograph has been framed in the device and the spider assembled at the back plate as above described, a front plate 12 of glass, mica, celluloid or other transparent material is placed over the sides as 125

shown in Figs. 1 and 4 and serves as a protector for the photograph and the colored face 11, the photograph with the number, as well as the face 11, being of course visible through the transparent plate 12. A suitable annular rim 13, which is preferably U-shape in cross-section is employed to hold the various parts in assembled position as shown in Fig. 4, while the numeral 14 indicates a loop carried by the rim 13 and by means of which the badge may be fastened to a chain, strap or other support as will be readily understood.

If desired, the loop 14 may be omitted and any suitable means employed for mounting the badge upon the coat or other article of the owner of the badge, or if desired, such badge may be used as a pocket piece.

In Fig. 5, I have shown a slightly modified form and use of the invention, a portion of the modified device being shown in section in Fig. 6. In this instance, a pocket case conventionally shown at C and made of leather or other material has an opening 25 c cut in one side thereof, while the arms 6' of the spider are extended through openings 15 in the rim 13' of the identifying device, and the extended ends of the spider are flattened to provide lugs 16 which may be inserted between the usual folds or plies 17-17' of the case, to retain the device in the case with its front face exposed as is clearly indicated in Fig. 5. When called upon to do so, the employee may open his case and exhibit his badge.

While I have herein shown and described a preferred embodiment of my invention, I wish it to be understood that I do not confine myself to all the precise details of construction herein set forth by way of illustration, as modification and variation may be made without departing from the spirit of the invention or exceeding the scope of the appended claims.

45 What I claim is:

1. As a means for rapidly identifying individuals by a casual inspection and adapted for identifying employees, an identification device comprising a body portion adapted to constitute a supporting frame for a photograph of the person to be identified, said photograph carrying indicia associating the original of the photograph with the particular employment, said frame having a configuration adapted to position the photograph and indicia distinctively to permit of rapid identification.

2. As a means for rapidly identifying individuals by a casual inspection and adapted for identifying employees, an identification device comprising a body portion having one face thereof marked with data identifying the concern using the device, a frame adapted to retain a photograph of the individual to be identified, and an identifying

number for the individual associated with said photograph, said frame having a configuration to position the photograph and number distinctively to permit of rapid identification.

3. As a means for rapidly identifying individuals by a casual inspection and adapted for identifying employees, an identification device comprising a badge or the like having a back plate marked with data identifying the concern using the device, a frame adapted to hold a photograph of the individual to be identified, said photograph carrying indicia associating the original of the photograph with the particular employment, said frame having a configuration adapted to position the photograph and indicia distinctively to permit of rapid identification, a transparent plate adapted to overlie the photograph and the indicia, and a retaining rim for securing the above mentioned parts in assembled position.

4. As a means for rapidly identifying individuals by a casual inspection and adapted for identifying employees, an identification device comprising a back plate marked with data identifying the concern using the device, a skeleton spider-like frame adapted to be placed against the inner face of the back plate and designed to constitute a support for a photograph of the individual to be identified, said photograph having an identification number associated therewith, said spider having a configuration adapted to position the photograph and number distinctively to permit of rapid identification, a transparent plate overlying said photograph and number, and a rim for retaining the back plate, the transparent plate and the skeleton frame in assembled position.

5. As a means for rapidly identifying individuals by a casual inspection and adapted for identifying employees, an identification device comprising a back plate having the outer face thereof marked with data to identify the concern using the device, a spider frame lying adjacent the inner face of the back plate and provided with means for supporting a photograph with the latter distinctively displayed to permit of rapid identification, a transparent plate overlying said spider frame, and means for retaining the back plate, the transparent plate and the spider frame in assembled position.

6. As a means for rapidly identifying individuals by a casual inspection and adapted for identifying employees, an identification device comprising a back plate having its outer face marked to identify the concern using the device, means at the inner face of the back plate for indicating a particular department of the concern employing the device, means located adjacent the inner face of the back plate for supporting a photograph of an individual with the photograph

- 41
9. As a means for rapidly identifying individuals by a casual inspection and adapted for identifying employees, an identification device comprising a circular back plate marked to indicate the concern employing the device, a spider frame comprising two concentrically arranged annular members 35 connected by radial arms, the innermost of said annular members being adapted to support a photograph centrally of the device, a transparent front plate overlying the spider frame and a rim for holding the assembled front plate, back plate and spider frame in assembled position. 40
10. As a means for rapidly identifying individuals by a casual inspection and adapted for identifying employees, an identification device comprising a body portion provided with a photograph carrying indicia associating the original of the photograph with the employment, and also having means to indicate a particular department of the concern employing the device, said photograph and department-indicating means being relatively positioned to produce a distinctive display of each of the identifying parts to permit rapid identification. 45
11. As a means for rapidly identifying individuals by a casual inspection and adapted for identifying employees, an identification device comprising a back plate having the name of the concern using the device marked thereon, the inner face of said back plate carrying distinctive color indicia to indicate a particular department of said concern; a frame for supporting a photograph arranged at the inner face of the back plate, said frame being positioned to permit distinctive exposure of the photograph and color indicia, a transparent front plate overlying the frame, and a rim for retaining the back plate, the front plate and the photograph frame in assembled position. 50
12. As a means for rapidly identifying individuals by a casual inspection and adapted for identifying employees, an identification device comprising a body portion having a back plate, a transparent front plate and a photograph supporting frame held between the two plates, a rim holding the two plates and the frame in assembled position, and projections extending beyond the rim for holding the device in mounted position on a suitable support. 55
- In testimony whereof I have hereunto set my hand in the presence of two subscribing witnesses. 60
